UNITED STATES PATENT OFFICE.

HENRY P. CLAUSEN, OF CHICAGO, ILLINOIS, ASSIGNOR TO AMERICAN ELECTRIC TELEPHONE COMPANY, OF CHICAGO, ILLINOIS, A CORPORATION OF ILLINOIS.

TELEPHONE-JACK.

SPECIFICATION forming part of Letters Patent No. 718,093, dated January 13, 1903.

Application filed May 8, 1902. Serial No. 106,436. (No model.)

To all whom it may concern:

Be it known that I, HENRY P. CLAUSEN, a citizen of the United States of America, and a resident of Chicago, Cook county, Illinois, 5 have invented a certain new and useful Improvement in Telephone-Jacks, of which the following is a specification.

In telephone systems it is usual to connect each subscriber's line with a spring-jack 10 mounted on a switchboard at the exchange or central station. These spring-jacks are adapted to receive the plugs of the operator's cord-circuit and to permit the latter in this way to connect one line with another. These 15 jacks are usually arranged in banks on the switchboard and are all located so as to be within reach of the operator.

It is the object of my invention to provide an improved construction whereby a number 20 of these jacks can be secured to a common mounting which is readily removable from the switchboard.

Another object is to provide a construction whereby the jacks on each mounting can be 25 brought closely together and whereby a comparatively large number of these jacks can be arranged upon a switchboard and assigned to the care of a single operator.

A further object is to provide a construction 30 which will not only bring all the jacks within a comparatively small compass, so as to facilitate the operation of connecting up different lines, but which will also reduce the amount of material to a minimum.

35 Another object is to provide a form of mounting which will be light and simple and at the same time rigid and of a character which will prevent it from having any tendency to warp or get out of shape.

40 It is also an object to provide certain details and features of improvement which will increase the general efficiency and which will tend to reduce the cost of manufacture and which will also tend to render a device of this 45 character more serviceable and satisfactory in use.

To the foregoing and other useful ends my

invention consists in matters hereinafter set forth and claimed.

In the accompanying drawings, Figure 1 is 50 a plan of a plurality of jacks secured to a common mounting involving the principles of my invention. Fig. 2 is a front elevation of the device shown in Fig. 1. Fig. 3 is a section on line 3 3 in Fig. 1. Fig. 4 is an enlarged section on line 4 4 in Fig. 1. Fig. 5 is a perspective of one of the jack-springs shown in Figs. 1 to 3.

As thus illustrated, my invention consists in what is commonly known as a "multiple" 60 jack—that is to say, a plurality of jacks secured to a common mounting and thus adapted to be collectively inserted in a switchboard. In other words, instead of mounting each jack separately a number of them are 65 secured together in a row upon a common mounting, which latter is adapted for ready insertion in and withdrawal from a switchboard.

As shown in Fig. 1, the device comprises, 70 preferably, a front strip A, of rubber or other suitable insulating material, and also a relatively thin back strip B. This back strip is preferably composed of both metal and rubber or like materials, the rubber being provided in the form of thin strips secured to the upper 75 and lower surfaces of the metal strip. This is more clearly shown in Fig. 3, wherein it will be seen that the back strip consists of the middle metal strip b and of the upper and lower rubber strips b' and b². The back strip 80 thus composed of superimposed layers or strips of conducting and insulating material is preferably connected with the front strip by means of metal end pieces C. These metal end pieces can be adapted to fit into ways or 85 grooves in the front of the telephone-switchboard. Each jack preferably comprises the upper and lower springs D and E and also the thimble or testing-ring F. The said springs and thimbles are, it will be observed, 90 arranged at regular intervals along the two strips, the thimbles affording sockets or openings in the front strip, through which the operator's cord-circuit plugs may be inserted

between the jack-springs. Each thimble or testing-ring is preferably provided with a rearwardly-extending portion *f*, which extends rearwardly and is clamped, in common 5 with the jack-springs, to the rearstrip B. The clamping means for this purpose preferably consists of the bolt G, adapted to pass through said portion *f* and also through the jack-springs and the back strip B. It will be seen 10 that this bolt is insulated from the jack-springs. As a means for preventing the jack-spring E from making contact with the portion *f* a strip of rubber or other like insulating material H can be interposed between the 15 two and clamped, together with the springs, upon the back strip by the said bolt G. Thus the said springs and the rearwardly-extending portion of the thimble or testing-ring are insulated from each other and secured firmly 20 in place upon the front and back strips involved in the construction of the multiple jack. As a means for preventing the jack-springs from being displaced the pins I are preferably driven through said springs and 25 also through the back strip. In each case these pins are insulated from the jack-springs by means of small rings or washers *i*, of rubber or like material. The jack-springs and also the portions *f* are all provided with laterally-projecting terminals *d*, *e*, and *f'*, to 30 which the various circuit-wires can be soldered or otherwise attached. In this way the jack-springs involved in each jack are secured firmly in place and the construction of the 35 entire device is reduced to a simple and inexpensive form.

The back strip, it will be seen, is preferably composed of a maximum of metal and a minimum of insulating material. In this way it 40 will be seen that greater strength and rigidity are secured. Furthermore, the distribution of the metal and insulating material tends to prevent warping. This, it will be seen, is for the reason that there is practically 45 the same amount of rubber on each side of the back strip, and consequently expansion and contraction due to change in temperature will not cause the strip to warp. Although simple and involving practically a 50 minimum of material, the device is strong and rigid and of such character that the different sets of jack-springs cannot possibly be loosened or in any way disarranged.

I claim as my invention—

- 55 1. A rubber front strip, a back strip comprising upper and lower sheets of rubber and an intermediate strip of metal, and a plurality of jack-springs suitably arranged and clamped upon said back strip.
- 60 2. A front strip having a row of openings, a back strip composed of upper and lower sheets of insulation and an intermediate strip of metal, and jack-springs clamped upon said back strip and arranged in sets opposite said 65 openings.

3. The combination of the apertured rubber

front strip, the composite back strip composed of alternate layers of rubber and metal, the metal end strips for connecting the said front and back strips, and the jack-springs 70 clamped upon opposite sides of said back strip.

4. The combination of a front strip of insulating material, a composite back strip composed of alternately-disposed layers of metal 75 and insulating material, the metal being in excess of the insulating material, suitable members for connecting the said front and back strips, and a plurality of jack-springs clamped upon opposite sides of said back 80 strip.

5. The combination of the apertured rubber front, the thimbles or testing-rings inserted in the apertures of said strip, the composite back strip composed of alternate layers of 85 rubber and metal, a plurality of jack-springs arranged upon opposite sides of said back strip, and clamping-bolts extending through the said jack-springs, and also through rearwardly-extending portions of the said thimbles or testing-rings, said bolts serving to 90 clamp the said parts firmly upon the said back strip.

6. A strip of metal, a sheet of rubber on each side of said strip of metal, jack-springs 95 arranged in pairs and mounted on opposite sides of said strips of metal and sheets of rubber, pins driven through said jack-springs and metal strips, and a pair of small rubber washers mounted on each pin and arranged 100 to insulate the latter from the said jack-springs.

7. The combination of the apertured front strip, the back strip composed of upper and lower strips of rubber and an intermediate strip of metal, jack-springs arranged upon opposite sides of said back strip, clamping-bolts passing through said back strip and jack-springs, pins driven through said jack-springs and back strip, and a pair of small 110 rubber washers mounted on each pin and arranged to insulate the latter from the said jack-springs.

8. The combination of the front strip, the thimbles or testing-rings mounted in said 115 front strip, the composite back strip composed of the upper and lower strips of rubber and the intermediate strip of metal, the jack-springs arranged above and below said back strip and clamped thereon by bolts, said bolts 120 being arranged also to pass through rearwardly-extending portions of said thimbles or testing-rings, strips of insulation between certain of the jack-springs and said rearwardly-extending portions of the thimbles or testing-rings, pins passing through the back strip 125 and jack-springs, and insulation between the pins and jack-springs.

9. In a device of the character described, the combination of a front strip consisting of 130 a piece of solid rubber provided with apertures, a back strip consisting of alternate

layers of rubber and metal so disposed or distributed that the unequal expansion and contraction of the rubber and metal will not tend to warp the structure, and a plurality of jack-
5 springs mounted upon said back strip and ar-
ranged in sets with reference to the apertures
in said front strip.

Signed by me at Chicago, Cook county,
Illinois, this 2d day of May, 1902.
